(57) **CLAIM**

The ornamental design for a “spool for fishing reel,” as shown and described.

DESCRIPTION

FIG. 1 is a perspective view of a spool for fishing reel showing the claimed design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a second top view showing a cut line for cross-sectional view;

FIG. 9 is a cross sectional view taken along line 9-9 in FIG. 8;

FIG. 10 is a detail view taken from location ‘10’ in FIG. 2; and,

FIG. 11 is the spool for fishing reel assembled with other parts of the fishing reel.

The evenly-spaced broken lines in FIG. 11 show unclaimed environmental subject matter and form no part of the claimed design. The dot-dash-dot broken lines in FIGS. 2 & 10 depict the locations of both a sectional view in FIG. 2 and a detail view of the spool threading in FIG. 10 and form no part of the claimed design.
